UNITED STATES PATENT OFFICE.

EDWARD E. GAINER, OF OKLAHOMA, OKLAHOMA, ASSIGNOR TO GEORGE E. LLEWELLYN,
OF BROOKLYN, NEW YORK.

APPARATUS FOR THE MANUFACTURE OF PLATE-ICE.

1,082,512.

Specification of Letters Patent. Patented Dec. 30, 1913.

Application filed November 8, 1910. Serial No. 591,219.

To all whom it may concern:

Be it known that I, EDWARD E. GAINER, a citizen of the United States, residing at Oklahoma city, in the county of Oklahoma and State of Oklahoma, have invented a certain new and useful Improvement in Apparatus for the Manufacture of Plate-Ice, of which the following is a specification.

The invention is an apparatus for the manufacture of plate ice.

In the particular embodiment of my apparatus which is hereinafter set forth, I employ a header from which depend a plurality of tubes closed at their lower ends, which enter for a sufficient depth, the water to be frozen. These tubes are kept filled with liquid ammonia, the gas developed being drawn off from the header and returned thereto after condensation and liquefaction, as already described. The ice forms upon the tubes first as cylinders which, as they enlarge in diameter, finally meet and form a single cake from which the tubes are subsequently withdrawn after the thawing off operation is accomplished.

In the accompanying drawings—Figure 1 shows a freezing tank in section with the header and depending tubes disposed therein, and the various connections and associated devices illustrated diagrammatically. Fig. 2 is a longitudinal section of one end of the header and connected depending tubes, showing the arrangement of the ends of the tubes in said header. Fig. 3 is a longitudinal section of the valves and couplings at the ends of the header.

Similar numbers of reference indicate like parts.

1 is a tank which contains the water to be frozen.

2 is a header supported upon the side walls of the tank in any suitable way. Depending from the header are a number of parallel vertical tubes 3 closed at their lower ends. Said tubes enter the bottom of the header and extend therein upward in the header for a short distance as indicated in Fig. 2. At one end of the header is an inlet for liquid ammonia; at the other end, an outlet for gas. The inlet communicates by pipe 4 with a valve casing 5, in which is seated a valve 6, Fig. 3. The outlet com-

municates by pipe 7 with a similar valve casing 8, in which is seated a valve 9. The casings 5 and 8 have flanges, by which they are detachably connected to similar flanges on similar casings 10, 11, in which casings are valves 12 and 13.

As shown in Fig. 3, the valves 12, 9, 6, 13 are frusto-conical in form, and are ground to fit accurately the correspondingly shaped seats in their casings. The bottoms of each pair of valves, as 12, 6, are also ground to fit accurately together when said valves are seated and when the flanges of their casings are coupled. Each valve is operated by means of a stem 14, headed at one end, seated in a threaded recess in said valve, and secured in said recess by an annular threaded collar 15. Each stem passes through a bonnet 16 bolted to the valve casing, and is threaded to pass through a bushing in a suitable standard 17 cast integral with said bonnet. On the end of the stem is the usual operating wheel.

To the valve casing 10 is connected a pipe 19 which communicates with a closed receptacle 20, and said receptacle 20 connects by pipe 21 with the suction end of the compressing pump 22. The delivery pipe 23 of said pump connects with one end of the condensing coil 24, disposed in a closed vessel 25. Said vessel 25 has an inlet 26 and an outlet 27 for the cooling water, and also communicates by a pipe 28 with a closed receptacle 29, which in turn by pipe 30 communicates with valve casing 11. From the bottom of receptacle 20 a pipe 31 extends to receptacle 29. From the pump delivery pipe 23 a by-pass pipe 32, provided with a valve 33, extends to the header 2 and is detachably connected thereto by a pipe communicating with said header and provided with a valve 35. A coupling 36 detachably connects pipe 32 to the header pipe.

The operation of the apparatus is as follows: The valves 12, 9, 6, 13 being opened, liquid ammonia from any suitable source is led through the pipe 37 into the receptacle 29, whence it flows by pipes 30 and 4 into the header 2 until it rises above the upper ends of the tubes 3. The liquid ammonia then flows down into all of the tubes 3 at the same time and fills them, so that at the beginning

of the ice-making process all of the tubes are filled with liquid ammonia and also the header up to the tops of the tubes therein. The ammonia then takes up the heat from the water in the tank 1, so that said water becomes frozen on the exposed outer surfaces of the tubes. The ice forms first as cylinders around the tubes, but as the cylinders increase in diameter they meet and be-
5 come welded together, finally forming a continuous cake 38, which is adherent to and supported upon said tubes. As the liquid ammonia receives heat from the water it vaporizes. The gas as it is formed is con-
10 stantly drawn off by the pump 22 through the receptacle 20, is compressed by said pump, and is delivered to the coil 24, where it becomes condensed to liquid which flows by pipe 28 to receptacle 29, and so to the
15 header. The receptacle 20 operates as a trap to catch any liquid formed between header and pump and to deliver the same through pipe 31 to inlet pipe 4. This opera-
20 tion of drawing off the gas, compressing and condensing it into liquid ammonia and re-
25 turning it to the header, goes on continually during the formation of the ice cake. During its progress the valves 33 and 35 are kept shut, and the coupling 36 may be discon-
30 nected. It is to be noted that the capacity of the pump is preferably to be such as con-
35 stantly to remove in a given time the gas produced in the same time. And the quantity of liquid returned to the header is to be such as will compensate for the lowering of the liquid level of the ammonia in the header, due to the vaporization taking place, so that by this means the liquid level in the header is maintained substantially constant.
40 Of course, any loss due to accidental circum-
stances, such as leaks, or the like, is easily compensated for by admitting into receptacle 29, small additional quantities of liquid ammonia from the original source. When
45 the ice cake on the tubes has attained the de-
sired thickness the pump is stopped, the valves 12, 9, 6, 13 are closed, and their flanged couplings disconnected. By any suitable hoisting means the header, tubes and
50 adherent ice cake are lifted from the tank and placed upon a tilting table or other support. The pipe 32, which may be flexible of any suitable length, is now coupled to the header, the valves 33, 35 opened. The pump
55 is again started, and now delivers warm compressed gas through pipe 32 into the header and above the liquid ammonia therein. This warm gas heats the tubes, and by its increased pressure raises the boiling point
60 of the ammonia confined in the header and duct system, so that said ammonia also be-
comes warmed. The result is to thaw the ice cake from the tubes 3, so that on lifting
65 the header the tubes may be drawn out of the cake. I prefer to remove the ice cake

from the tank prior to thawing off, but the operation may be done, if desired, in the tank. The valves 12, 9, 6, 13 are closed as before, the pipe 32 is connected and valves 33, 35 opened, and when the header and tubes are lifted, the ice cake remains in the tank and may be removed by the usual tongs or other lifting out means.

As previously stated, this apparatus does away with all heating of a non-congealable liquid, such as brine, and with all the apparatus for containing and circulating the same. The result is not only a large economy in cost of the apparatus, but an even greater one in the expense of manufacture, for one transformation of energy is obviated. In addition, the speed of ice production is notably enhanced.

I claim:

1. An ice making apparatus comprising a header having a liquid inlet, a plurality of tubes each closed at its lower end depending therefrom, and means for causing said liquid to flow simultaneously into said tubes.

2. An ice making apparatus comprising a header having a liquid inlet, and a plurality of tubes depending from said header: each of said tubes extending at its upper end into said header for a predetermined distance and closed at its lower end.

3. An ice-making apparatus, comprising a tank, a header, a plurality of tubes, each closed at its lower end, depending from said header into said tank and extending at its upper end into said header, means for de-
100 livering a volatile refrigerating liquid into said tubes, and means communicating with said header above the upper ends of said tubes for drawing off gas therefrom.

4. An ice making apparatus comprising a tank, a header, a plurality of tubes each closed at its lower end depending from said header into said tank, means for delivering liquid ammonia into said header and tubes, means for withdrawing the gas due to evap-
101 oration of said liquid ammonia from said header, means for liquefying said gas, and a duct for returning said liquid to said header.

5. An ice making apparatus comprising a tank, a header, a plurality of tubes each closed at its lower end depending from said header into said tank, means for delivering liquid ammonia into said header and tubes, means for withdrawing the gas due to evap-
11 oration of said liquid ammonia from said header, means for compressing said gas, means for liquefying said compressed gas, a duct delivering said liquefied gas to said header, a valve controlling said duct, a by-
12 pass delivering said compressed gas into said header, and a valve controlling said by-
pass.

6. An ice making apparatus comprising a header having an inlet for liquid ammonia

and a gas outlet, a plurality of tubes each closed at its lower end depending from said header, a gas pump, a suction duct leading therefrom communicating with said gas outlet, a trap for liquid in said suction duct, and a duct leading said liquid from said trap to said header inlet.

In testimony whereof I have affixed my signature in presence of two witnesses.

EDWARD E. GAINER.
